Primary Examiner — Karen E Eldridge Powers*(74) Attorney, Agent, or Firm* — Nixon & Vanderhye PC(57) CLAIM

I claim the ornamental design for a corset, as shown and described.

DESCRIPTION

FIG. 1 is a perspective view of the corset;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings illustrate lines of stitching that are part of the claimed design.
